COMBINATION VEHICLE CHASSIS AND CAB

Russell E. Jones, 621 Adena Road,
Chillicothe, Ohio 45601

Filed Aug. 15, 1968, Ser. No. 13,149

Term of patent 14 years

Int. Cl. D12—09

U.S. Cl. D14—3

Des. 215,927

PAGE 2

FIGURE 1 is a side elevational view of the combination vehicle chassis and cab;

FIGURE 2 is a similar view showing the other side of the combination vehicle chassis and cab;

FIGURE 3 is a plan view of the combination vehicle chassis and cab;

FIGURE 4 is a front end view of the combination vehicle chassis and cab; and

FIGURE 5 is a rear end view of the combination vehicle chassis and cab.

The dominant features of my design reside in the portions shown in full lines.

I claim:

The ornamental design for a combination vehicle chassis and cab, substantially as shown and described.
